UNITED STATES PATENT OFFICE.

PETER MATHIESON, OF WALTHAM, MASSACHUSETTS, ASSIGNOR TO DRAPER CORPORATION, OF HOPEDALE, MASSACHUSETTS, A CORPORATION OF MAINE.

COMBINED SHUTTLE CHECK, BINDER, AND BOBBIN GUIDE FOR LOOMS.

Application filed August 6, 1923. Serial No. 655,860.

To all whom it may concern:

Be it known that I, PETER MATHIESON, a subject of the King of Great Britain, and a resident of Waltham, in the county of Middlesex and Commonwealth of Massachusetts, have invented certain new and useful Improvements in Combined Shuttle Checks, Binders, and Bobbin Guides for Looms, of which the following is a specification.

10 This invention relates to a combined shuttle check, binder, and bobbin guide for looms.

Among the objects of the invention is to provide a binder of this class, which not only functions as a check and bobbin guide but also is of such construction as to eliminate yarn breakage heretofore due to the pinching of the yarn between the shuttle and the binder.

20 A further object of the invention is to provide a combined binder and check which is preferably of less length than the shuttle and which, when in binding contact with the shuttle, contacts therewith for approximately the entire length of the binder, and which in its movements toward and from the shuttle travels in parallelism.

It is a further object of the invention to so construct the binder that it may be readily 20 adjusted to accommodate large or small shuttles to a nicety, and its binding pressure upon a shuttle may be regulated, which last adjustment also serves to regulate its checking powers.

35 Another object of the invention is to so construct and arrange the binder that it occupies the most advantageous position relatively to the shuttle for checking and binding purposes, and which position conveniently affords an opportunity for the binder to serve as a bobbin guide under certain conditions, during bobbin replenishing action of the loom.

As it is an object of the invention to apply 45 the improved binder to existing looms, it is also an object to simplify structure and to so arrange the binder and the protector or dagger rod operating lever, that they are mounted as a unit, which may be readily attached to existing looms with but slight expenditure of labor and time.

Heretofore considerable trouble has been experienced in the breakage of the yarn, or filling of the shuttle, which was due to the 55 fact that a binder was used which had con-

tact with the shuttle wall to the full extent of the shuttle height, with the exception of the groove or channel of the shuttle at the side thereof, in which the yarn was supposed to lay.

60 It will be readily understood that the yarn did not always lay in this groove when the shuttle was boxed, because of kinks, or undue slack, and consequently was pinched between the shuttle wall and the binder, at 65 which time breakage had to occur.

The present invention eliminates this fault by providing a binder that does not contact with the shuttle for its full height, but contacts with it only at the upper portion, above 70 the yarn groove of the shuttle, thus leaving space below of an appreciable amount, in which the yarn may lay without fear of being cut or broken by being pinched between the shuttle and the binder.

75 Also the binders used heretofore were pivoted at the outer ends and were held in the path of the shuttle by comparatively light leaf springs, and the protector rod spring, which were not readily adjustable, and which when struck by the shuttle swung outwardly on the arc of a circle.

Such binders were not sufficient in themselves to both check and bind a shuttle, but required assistance, which was supplied by 80 separate and distinct devices called shuttle checks.

85 The pivoted binder was generally of such construction that only a very small portion of it contacted with the shuttle when it was 90 on its way into the box, and also when it arrived there, and consequently the frictional surface presented was of such small area that its checking ability was almost nil, hence the reason of the above mentioned 95 check devices.

In the present invention, the binder is of 100 such arrangement that checking of the shuttle commences immediately upon shuttle and binder contact, and increases as the shuttle enters further into the box until shuttle flight is stopped. This increase is due to the fact that as the shuttle enters the box it encounters more and more binder surface until approximately the entire length 105 of binder is in contact, at which time the shuttle is well in check and the binder is exerting its effort to retain it immovable in its finally checked position.

Furthermore the protector rod spring, in 110

the past, had to be of such stiffness as to function in its usual capacity as well as to bear the brunt of shuttle impact with the binder and in fact was the main binder operating spring.

In the invention herewith, binding action does not depend wholly upon the protector rod spring, as another and more accessible spring, easily adjusted, is employed for that purpose.

Another feature of the invention consists in the arrangement of the binder whereby the shuttle may be manually released from binding action for the purpose of shifting 15 the position of, or inserting a new shuttle in the box, by means primarily intended for another purpose but being readily accessible and conveniently located for this purpose.

The invention further consists in certain 20 novel features of construction and arrangement of parts which will be fully understood from a description of the drawings and the claims hereinafter given.

Of the drawings:

25 Figure 1 represents in plan view a sufficient portion of the lay of a loom to enable the invention to be understood.

Figure 2 a front side elevation of the parts shown in Figure 1.

30 Figure 3 a view looking toward the left Figure 2, some of the parts being omitted for clearness.

Figure 4 a view similar to Figure 1 but showing the position the binder and attachments assume before the shuttle enters the box.

Figure 5 a section on the line 5—5 Figure 2 some of the parts being omitted for clearness.

40 Figure 6 an enlarged top plan view of some of the parts shown in Figure 1 to further illustrate the means to adjust the binder.

Like characters represent like parts 45 throughout the several figures of the drawings.

Referring to the drawings:

The drawings herewith illustrate the invention as applied to a loom wherein the binder is on the front side of the shuttle box, but it will be understood that the invention is equally applicable to other types of looms wherein the binder is located at the rear side of the shuttle box.

55 It is not therefore the intention to limit the invention to the precise construction and arrangement shown as changes might be made therein without departing from its spirit and scope.

60 The lay 10, shuttle box wall 11, picker 12 and protector or dagger rod 13 are or may be of any usual or suitable construction such as are commonly used in automatic, plain, dobby or box looms.

65 The shuttle 14 is one such as is used in

automatic filling, replenishing looms to which this invention is applicable.

As it is an object of the invention to construct a binder that may be applied to existing looms, it is especially desirous that 70 it be simple, and easily applied at small cost.

To accomplish this, the binder 15 and its cooperating parts are in the present instance, mounted on a bracket 16, which is attachable to the lay by means of bolts 17.

The bracket 16 has ways 18 formed therein, by means of which the binder 15 is guided in parallelism, transversely of the lay 10.

Pivoted at 20 to the left end of the bracket 16 is a lever 21, which also has connection with an extension 22 of said binder 15, to be later described, and which is under the control of a spring 45 adjustably mounted 85 on a part 24 of the bracket 16.

A protector rod control lever 25 is pivoted at 26 to a yoke or bridge 27 under which the lever 21 is free to move within the limitations of the bridge uprights 29 and 30, which limitations may be determined to suit the occasion of use.

This lever 25 also has connection with the binder extension 22 which will now be explained.

The extension 22 has a reinforcing rib 31, see Figures 5 and 6, in which are the threaded holes 32 and 33 adapted to receive a stud screw 34.

Levers 21 and 25 have elongated holes 35 and 36 respectively, adapted to receive an eccentric sleeve 37, having the squared nut like head 38, and adapted to be entered by the screw 34.

To adjust the binder 15, toward or from 105 the shuttle 14, the screw 34 will be turned to release the sleeve 37 and thereafter the said sleeve will be turned in the proper direction to give the required adjustment.

In the event that a wider shuttle is to be 110 used, the screw will be released from the hole 32 and inserted in the hole 33 to obtain the initial adjustment, and thereafter, the sleeve 37 will be manipulated to obtain a finer adjustment.

As the dagger, not shown, must be operated in timed relation with the boxing of a shuttle, the lever 25 is used for this purpose.

The protector or dagger rod 13 which carries the dagger as usual, has a controlling spring 40 which normally presses the finger 41 fast on the rod 13, against the left end of the lever 25, so that, when the shuttle enters the box, outward movement of the lever 25 will cause the finger 41 to turn rod 13 against the action of spring 40, at which time the dagger will be removed from operating position with respect to the knock-off, not shown.

The spring 40 need not be any stronger than is necessary for it to function as just described, as reliance need not be placed thereon for it to function as a binder spring.

5. Adjustable frictional contact of the binder 15 and shuttle 14 is obtained by means of the spring 45, the tension of which may be regulated by means of the thumb nut 46.

An important feature of the invention 10 consists in the manner in which the binder 15 contacts with the shuttle 14, so that the yarn leading from the shuttle escapes the possibility of becoming pinched between the binder and shuttle, which as is well known 15 breaks or cuts the yarn.

For this purpose the binder 15 having the usual shuttle contact face 47, of leather or similar material, is cut away as at 48, so that only its upper portion as seen in Figure 5, 20 contacts with the shuttle, thus leaving space below in which the yarn may lay without fear of harm.

When it is desired to release a shuttle from the action of a binder for the purpose of 25 withdrawing it from the box, or for the purpose of inserting a shuttle in the box, either one of the levers 21 or 25 may be grasped and pressed forwardly by one hand, while the other manipulates the shuttle.

30. The binder 15 is very conveniently positioned and shaped to function as a bobbin guide when applied to a so called magazine or automatic loom.

The top face of the binder is bevelled as at 35 49 for its entire length, so that in case a bobbin upon leaving the magazine 50, see Figure 5, should by accident assume an angular position as indicated by the broken line $y-y$ Figure 1, it will, upon descent of the transfer hammer 51, be guided by the bevel 49 into the shuttle.

It is not known that a binder together with its control spring, and a protector rod control lever have ever been mounted as a 45 unit and adapted to be applied to existing looms.

Nor is it known that a binder, movable transversely of the lay in parallelism, and being so constructed and arranged as to 50 function as a bobbin guide at certain times has ever been used.

Having described the invention I claim:

1. A shuttle binder mounted for movement in a rectilinear path towards and from 55 its shuttle binding position, means for adjusting the binder along said path to accommodate different widths of shuttles, and separate means for adjusting the binder to different positions in said path whereby the 60 binding action of the binder on the shuttle in use may be regulated.

2. A combined shuttle check and binder mounted for movement in a rectilinear path toward and from its shuttle checking and 65 binding position a binder spring acting upon

the binder, means connected to the binder whereby its checking and binding action may be regulated in accordance with the shuttle in use, a bracket carrying said check and binder, binder spring and regulating 70 means as a unit, and means for attaching said bracket and parts carried thereby to the lay of existing looms.

3. In a loom, the combination of the lay and protector rod, a combined shuttle check and binder mounted on the lay independently of the protector rod, an element fulcrumed on the lay and connected to the binder, and a finger on the protector rod overlying said element, said check and binder 75 and said fulcrumed element constructed and arranged for application as a unit to existing looms.

4. A combined shuttle check and binder adapted to be moved toward and from a shuttle in a rectilinear path; means to vary the checking and binding powers of said check and binder; separate means to adjust said check and binder to different positions in its rectilinear path of movement to accommodate shuttles of different widths; a protector rod mounted on the lay independently of the check and binder; means under the control of said check and binder adapted to control the protector rod; said check and binder, and all of said means except the protector rod being mounted as a unit and adapted to be applied to existing looms. 85

5. In a loom, the combination of a shuttle binder having a bobbin guide extending 90 lengthwise of the binder to an extent substantially the length of the wound filling carrier for directing a filling carrier into the shuttle should such filling carrier be improperly positioned as it is being transferred, and means acting upon the binder to hold the shuttle in filling carrier receiving position. 95

6. In a loom, the combination of the lay 100 and shuttle box, a bracket having binder guides and mounted on the lay, a shuttle binder mounted in said guides on the bracket for rectilinear movement towards and from the shuttle in the shuttle-box, means for moving the binder in its guides, and means for regulating the binding action of the binder. 110

7. In a filling replenishing loom, the combination of the replenishing shuttle box, a binder for acting upon a shuttle in said box, 115 a transerrer for transferring a bobbin from a source of supply into the shuttle, and a guide carried by the binder and extending longitudinally along the binder a distance substantially the extent of the windings on the bobbins to be transferred for engaging and directing the bobbin into the shuttle should the bobbin become out of parallelism with the shuttle as it is transferred thereto by the transerrer. 120

8. In a loom, the combination of the lay, a shuttle box, the front of which has an opening extending longitudinally the full length of the shuttle in which the filling may rest, and a binder for acting upon the side of the shuttle only above the thread groove formed in the side of the shuttle.
9. In a device of the class described, a lay; a shuttle box on said lay and formed in part by a wall and a binder, a binder adapted to be bodily moved toward and from said wall in a line perpendicular thereto; a bracket on which said binder is guided; means mounted on said bracket to normally move said binder toward said wall; and protector rod operating means mounted on said bracket.
10. In a device of the class described, a lay; a shuttle box on said lay and formed in part by a wall and a binder; a binder adapted to be bodily moved toward and from said wall in a rectilinear path; a bracket mounted on the lay and on which said binder is supported and guided in its rectilinear path; means mounted on said bracket and coacting with said binder to vary the power of said binder; and protector rod operating means mounted on said bracket and under the control of said binder.
11. In a device of the class described, a lay; a shuttle box on said lay composed in part of a wall and a binder; a binder adapted to be moved toward and from said wall; a bracket on which said binder is supported and guided for movement in a rectilinear path perpendicular to said wall; means mounted on said bracket and coacting with said binder to vary its power; and separate means to adjust said binder to accommodate large and small shuttles.
12. In a loom, the combination of the lay and shuttle box, a bracket mounted on the lay, a binder mounted on the bracket, a lever pivotally supported on the bracket and connected to the binder, a spring acting through the lever on the binder, a protector rod, a second lever connected to the binder, and means acting in timed relation with said binder to control the protector rod through said second lever.
13. In a loom, the combination of the lay and shuttle box; a bracket mounted on the lay, a lever mounted on the bracket and connected to the binder, a spring carried by the bracket and acting on said lever that said binder, lever, and spring may be applied with the bracket as a unit to existing looms.
14. In a loom, the combination of the lay and shuttle box, a bracket secured to the lay and having a guideway, a binder mounted for sliding movement in said guideway to act upon the shuttle, a spring controlled lever connected to and for acting upon the binder, means for adjusting the connections between the binder and lever to accommodate different sized shuttles, and eccentric means for adjusting the binding action of the binder on the active shuttle.
15. In a loom, the combination of the lay and shuttle box, a bracket secured to the lay and provided with a guideway, a binder mounted in said guideway for rectilinear movement towards and from the shuttle, a lever pivotally mounted on the bracket at one side of the guideway and connected to the binder, and a spring acting on said lever to force the binder against the shuttle.
- Signed by me at Waltham, Middlesex County, Massachusetts this 30th day of July, 1923.
- PETER MATHIESON.
